INVENTOR
Clarence D. Platt

C. D. Platt
ATTORNEY

UNITED STATES PATENT OFFICE.

CLARENCE D. PLATT, OF BRIDGEPORT, CONNECTICUT.

ELECTRIC SWITCH.

Application filed January 10, 1925. Serial No. 1,560.

To all whom it may concern:

Be it known that I, CLARENCE D. PLATT, a citizen of the United States of America, residing at Bridgeport, county of Fairfield, 5 State of Connecticut, have invented a new and useful Electric Switch, of which the following is a specification.

My invention relates particularly to an enclosed safety switch having a quick break 10 mechanism.

The main object is to provide a compact, reliable and practical but inexpensive construction.

The invention is particularly applicable 15 to any ordinary enclosed switch having the usual hinged blades and oscillating operating crank. In the preferred form I provide an operating plate member which has two spaced apart projections for alternately 20 engaging one arm of the crank to move it positively back and forth. This crank arm is resiliently connected to one of the projections by a spring so that when the projection is moved away from the arm it compresses 25 the spring and stores up power to throw the crank with a snap action as soon as the blades have been released from the stationary contact by the positive action of the other projection.

30 Figure 1 is a front view of a switch embodying improvements of my invention, the cover of the casing being open and broken away.

Figure 2 is a sectional view on the plane 35 of the line 2—2 of Fig. 1, looking in the direction of the arrows and showing a side view only of the switch base proper.

Figure 3 is a section on the plane of the line 3—3 of Fig. 2 looking in the direction 40 of the arrows but on an enlarged scale.

Figure 4 is a perspective view of the operating plate and spring support.

Figure 5 is a sectional view of the quick-break link.

45 The case or receptacle 7 may be of any suitable type and provided with any suitable closure and fastening device as is common in structures of this character.

The switch proper consists of an insulating base 8 on which are mounted the stationary switch contacts or jaws 9 and the hinged blades 10. In this case the blades are suitably connected to an insulating cross-bar 11.

55 The operating crank 12 may be of any

suitable design mounted in any suitable manner to permit oscillation, preferably about the axis of the blades or approximately parallel therewith. The cross-bar of the crank is connected to the cross-bar 11 in any 60 suitable manner, for instance, by the link 13.

In the ordinary switch of this type some form of external handle such as 14 is usually provided. In this case, however, the important features are enclosed within the box 65 itself. The plate 15 is what may be termed the operator. This is pivotally mounted on one wall or the box, for instance, by being connected to the bearing washer 16 and the outer washer 17 by means of one or more 70 rivets 18. This plate 15 is provided with two projections 19 and 20 which extend inwardly into the path of movement of one arm of the crank 12 so that as the plate is oscillated they engage, alternately, the opposite sides of the arm. A link 21 which embraces the crank arm passes through the opening 22 in the projection 19. A spring 23 which is mounted on this U shaped strap link 21 is held in place by the ring member 80 25 and the turned over or hook-like ends of the link 21.

In assembling the parts the link 21 is slipped around the arm of the crank 12 and inserted through the opening 22. The spring 23 is then slipped on to the link 21. The ring 25 may then be slipped on to the end of the spring. The spring is then compressed by pushing down upon the ring so that the top of the ring passes beyond the turned over ends of the link and when in this position, the ends of the link which have been sprung together to allow the ring to pass over them, will spring back to their original position so that, as pressure upon the ring is released, the ring will seat itself in the turned-over ends of the link and will be retained in that position for the normal operation of the switch. In order to remove the spring, ring and strap, the assembling 90 operation is reversed.

Obviously the link may be of strap form or may be of spring wire.

When the operator 15 is oscillated clockwise, as viewed in Fig. 2, by the handle or otherwise, the projection 19 on the operator plate compresses the spring 23 and swings the link to position as shown in dotted lines. The flange or projecting lug 20 soon engages the crank arm, however, and forcibly moves 105 110

it and the switch blade towards the open circuit position, as soon as the frictional resistance of the contact jaws on the switch blades decreases to a sufficient extent, the 5 spring 23 acting from the link 21 throws the crank and switch blades suddenly to the open circuit position with a quick break or snap action. In this opening movement the crank arm brings up against the projection 10 19 which serves as an abutment for it.

A stop 26 may be provided on the outside 15 of the box to limit the throw of the handle and to serve as an anchorage for a sealing wire or lock. Another stop 27 may be provided on the inside of the box to limit the throw of the crank. By placing this stop 27 in the path of the end of the link 21 it serves to resiliently check the opening movement of the switch.

20 I claim:

1. A safety switch comprising a casing, a knife blade switch mounted therein, an oscillating crank connected to the switch blades, an oscillating plate operator having 25 spaced-apart projections for engaging opposite sides of one arm of said crank, a spring, and means for connecting said crank arm to said plate to compress said spring when the plate is being operated to open 30 the switch.

2. In an enclosed switch an operating crank arm, an operator plate having spaced-apart projections for engaging said crank arm, a link connected to said crank arm, and 35 a compression spring mounted on said link

and bearing against one of the projections on said plate.

3. In an enclosed switch an oscillating crank arm, a plate having spaced-apart projections for engaging said crank arm, a strap 40 surrounding said crank arm and passing through one of said projections, a spring mounted on said strap and engaging a projection through which said strap passes, and means for operating said plate.

4. In an enclosed switch a switch operating crank arm, an operating plate having a projection, a link connected to said crank arm, a compression spring supported by said link between said projection and the outer 50 end of said link.

5. In a switch a crank arm, an operating plate having a projection for engaging said arm, a strap link embracing said arm and having a hook on the opposite end and a spring on said link interposed between said projection and said hook.

6. In a switch, a crank arm, an operating plate having a projection for engaging said arm, a strap link embracing said arm a ring 60 on the other end of said arm and a spring interposed between said projection and said ring.

7. In a switch, a crank arm, an operator having two spaced apart projections adapted 65 to engage said arm, a strap link embracing said arm, a spring on said link abutting against one of said projections and means for holding said spring on said link.

CLARENCE D. PLATT.
